UNITED STATES PATENT OFFICE.

ROBERT O. KING, OF BUFFALO, NEW YORK, ASSIGNOR TO KING CONSTRUCTION COMPANY, OF NORTH TONAWANDA, NEW YORK, A CORPORATION OF NEW YORK.

TRUSS-COUPING.

1,165,419.

Specification of Letters Patent. Patented Dec. 28, 1915.

Application filed May 1, 1911. Serial No. 624,310.

To all whom it may concern:

Be it known that I, ROBERT O. KING, a citizen of Canada, residing at Buffalo, in the county of Erie and State of New York, 5 have invented new and useful Improvements in Truss-Couplings, of which the following is a specification.

This invention relates to trussing which is more particularly designed for use on the 10 roofs of green houses but which may also be used on the roofs of other buildings.

The purpose of this invention is to provide simple, inexpensive and effective fixtures for use in trusses for roofs which permit of being quickly and properly erected, which will permit the struts to swing freely 15 and adapt themselves to the strains of the guys and tie rods and thus avoid breakage, and which permit of readily assembling the 20 parts and retaining them in a position in which they are alined and present a regular appearance.

In the accompanying drawings Figure 1 is a fragmentary vertical transverse section 25 of the roof of a green house equipped with my improved roof trussing fixtures or fittings. Fig. 2 is a perspective view of one of the clips of the coupling connecting the upper end of the main strut with the rafter and upper and lower guys. Fig. 3 is a vertical section, on an enlarged scale, in line 30 3-3, Fig. 1, showing the means for coupling or connecting the upper end of the main strut with the rafter and the adjacent guys. Fig. 4 is a horizontal section of the 35 same in line 4-4, Fig. 1.

Similar letters of reference indicate corresponding parts throughout the several views.

40 That part of the green house shown in the drawings for illustrating my improved trussing comprises a post 1, an elevated ridge 2, an inclined rafter 3 preferably of tubular form connected at its upper and lower ends by upper and lower fittings 4, 5 with the ridge and post, respectively, an inclined brace 50 connecting the post and rafter, a gutter 6 arranged at the upper end of the post, purlins 7 arranged on the rafter, 45 a sash bar 8 arranged on the purlins and extending from the ridge to the gutter, clips 9 connecting the rafter, purlins and sash bars, and glass panes 10 mounted on the sash bars.

The trussing for each rafter with which 55 my improvements are associated comprise a

main strut 11 arranged below the central part of the rafter, a pair of lower truss rods 12, 12, arranged lengthwise on opposite sides of the brace 50 and connected at their outer ends with the outer or lower rafter fitting 5 while their inner ends are operatively connected with the lower end of the main strut, a lower intermediate strut 13 arranged between the lower truss rod and the rafter, an upper sectional truss rod 14, 60 15 connected at its outer end with the lower end of the main strut while its inner end is connected with the upper rafter fitting 4, an upper intermediate strut 18 arranged between the upper truss rod and the rafter, a 65 main tie rod 19 connected at one end with the lower end of the main central strut and with the truss rods, a wind tie rod 20 connected at one end with the lower end of the upper intermediate strut and the upper 70 75 truss rod, a lower guy rod 16 extending from the lower end of the lower intermediate strut and lower truss rod to the upper end of the main strut, and an upper sectional guy rod 17 extending from the upper 80 end of the main strut to the lower end of the upper intermediate strut and upper truss rod, as shown in Figs. 1 and 2.

The coupling for connecting the upper end of the main strut, rafter and guy rods is 85 constructed as follows: 53 represents two clips each of which is provided at its upper end with a curved jaw 54 adapted to engage with one side of the rafter and at its lower end with a transverse opening 55 and a 90 laterally projecting perforated ear 56. On its inner side and concentrically around the opening 55 the clip is provided with a circular collar 57 and between the opening 55 and the jaw of this clip the same is provided with an intermediate opening 58. The two clips 53 are placed with their jaws in engagement with opposite sides of the rafter and their collars in engagement with each other and the same are held in this 95 position by means of a main transverse coupling bolt 59 passing through the lower openings 55 and an intermediate coupling bolt 60 passing transversely through the intermediate openings 58. The upper end 100 of the main strut is arranged between the lower ends of the clips 53 and an opening 61 in its upper end receives the collars 57 of these clips. The latter are preferably made by casting the same in molds made by the 105 110 115 120 125 130 135 140 145 150 155 160 165 170

same pattern but when the two clips are secured to each other with the faces of their jaws and the ends of their collars opposing each other the ear 56 of the same project laterally in opposite directions. One of the ears 56 receives the shank 62 which is bent laterally in one direction on one of the guy rods and secured therein by a screw nut 63 bearing against the outer side of said ear while the 10 other ear receives a shank 64 bent laterally on the end of the other guy rod and secured therein by a screw nut 65 bearing against the outer side of the last mentioned ear, as shown in Fig. 4. This connection between 15 the main strut and the rafter and guy rods permits the strut to swing and turn under the strains to which it is subjected without liability of breakage and still maintain a

firm and reliable connection between the parts with which the strut is associated. 20

I claim as my invention:

A truss coupling comprising two clips each of which is provided at its upper end with a jaw and at its lower end with an opening, a collar around said opening and a laterally projecting ear, said clips engaging their jaws with opposite sides of a main truss member, supporting an auxiliary truss member on their collars and having their ears connected with other truss members. 25 30

Witness my hand this 29th day of April, 1911.

ROBERT O. KING.
